FUEL SUPPLY SYSTEM

Fritz Stephan, Chicago, Ill., assignor, by mesne assignments, to Stephan Engineering Corporation, a corporation of Delaware

Application May 20, 1931. Serial No. 538,742

7 Claims. (Cl. 103—173)

My present invention relates, generally speaking, to a fuel supply system, and more particularly to a direct injection pump system for supplying fuel to the cylinders of an internal combustion engine or the like.

The device will be better understood from a detailed description of the accompanying drawings. In these drawings:

10 Figure 1 illustrates the device completely assembled, drawn approximately to size;

Figure 2 is a top view of the device;

15 Figure 3 is an enlarged longitudinal section through the device taken on the line 3—3 of Figure 2;

Figure 4 is an enlarged cross-section taken on line 4—4 in Figure 3 and illustrating the check valve in the outlet connection of the device;

20 Figure 5 is a diagrammatic perspective view, with several parts broken away, of the key and locking arrangement between the piston, the valve stem, and the sleeve on the pump piston;

Figure 6 is a diagram drawn on an enlarged scale and illustrating the piston and valve action on a straight plane;

25 Figures 7 and 8 illustrate, on an enlarged scale, another embodiment of a locking provision for the valve cooperating with the pump piston;

Figures 9 and 10 represent a further embodiment of a locking provision between the pump piston and the valve; and

30 Figure 11 is a partial view, in section, of a modified embodiment of the auxiliary piston.

Referring now particularly to Figures 1 and 2, these figures illustrate the device completely assembled and ready for mounting on an engine.

35 The device comprises a frame member designated by the numeral 1 having a flange 2 and laterally extending mounting projections integral with this flange 2, designated, in Figure 1, by the numerals 3 and 4.

40 There are three such mounting projections provided on the frame member 1 as is particularly indicated in Figure 2, these projections being designated by the numerals 3, 4 and 5. A number of cylinders are circularly disposed on the frame member 1 as shown.

45 These cylinders are indicated in the drawings Figure 1, by the numerals 6, 7, 8 and 9. There are as many pump cylinders circularly disposed on the frame member 1 as there are engine cylinders pro-

50 vided on the engine on which the device is used. A closing member 10 is placed on top of the frame member 1 for holding the circularly arranged pump cylinders in position. This closing mem-

55 ber is provided with outlet projections, one for each cylinder, and attached to each outlet pro-

jection by means of a nut is a feed line to the corresponding engine cylinder. The nuts holding the feed lines to the various outlet portions of the closing member 10 are designated in the drawings Figures 1 and 2 by the numerals 11 to 16, inclusive. The feed line joints are designated by the reference numerals 17 to 22, inclusive, and attached to each joint is a feed line as indicated by like primed numerals. In each of these outlets is disposed a check valve which will be described later on in detail. A cap or shell 23 is placed on top of the closing member 10. This shell 23 is provided with an inlet projection to which may be attached the feed inlet line 24 by means of the nut 25.

60 The above described parts are held in unitary assembly by means of a bushing member 26 which has an internal thread engaging a thread on the upper portion of the main frame 1.

65 A lower housing member 27 is attached to the mounting extensions 3, 4 and 5 by means of tubular screws projecting through the laterally projecting mounting extensions on the main frame 1 and through corresponding lateral extensions on the housing 27 which register with the extensions on the frame, as shown particularly in Figure 1. The main frame member 1 and the housing 27 are held together in a unitary assembly and the device may be mounted on an engine by means of suitable bolts projecting through the tubular screws mentioned above which hold the housing 27 and the frame 1 in assembly.

70 The relation between the auxiliary pistons mentioned at several places before and the main pistons reciprocating within the circularly arranged cylinders will be altered by a shifting of the cam, thereby changing the stroke of the pistons and determining the volume of fuel ejected by the pistons through the feed lines.

75 The precise operation of the device will be clearly understood after the interior arrangement of the details and the particular operation of the pistons is known. However, I wish to call attention at this place to the simplicity of the design as evident from the above description with reference to the Figures 1 and 2. The entire device is held in unitary assembly solely by the member 26.

80 When this member is removed, the cap 23, the member 10 as well as the cylinders can be lifted off without any difficulty and without the unscrewing of any other part. Access

85 may be had to the interior of the housing 27 by merely removing the three tubular screws which hold the housing 27 in engagement with the main frame 1. The device is designed for

60

65

70

75

80

100

105

110

attachment to a gasoline engine of known design. It may be attached in substitution of the carburetor and the mounting is made simple and efficient since it is only necessary to insert three bolts or the like through the tubular screws which hold the housing 27 and the main frame 1 in assembly. The top shell 23 can be turned around to adjust the fuel inlet 24 to any position radially to the device. The attachment of the fuel line 10 24 can therefore be accomplished with ease since the device lends itself readily to any engine construction.

I shall now describe the interior assembly of parts with reference to the Figure 3. This figure is an enlarged cross-section taken along the lines 3-3 in Figure 2 looking in the direction of the arrows. I have applied the same reference numerals to identical parts in order to facilitate the description.

20 Referring now to Figure 3, it will be seen that the main frame member 1 has a central portion which is joined in its lower part by the integral flange portion 2. Projecting from this flange portion 2 are three lateral extensions each provided with a threaded hole. One of these extensions is shown in Figure 3 and designated by the numeral 3. It corresponds to the extension 3 shown in Figure 1. In the flange portion 2 are as many openings as there are pump cylinders. 25 The cylinders, such as the cylinders 6 and 9, are each provided with a shoulder such as 32, 33, respectively, and these shoulders engage correspondingly recessed or turned down portions on the slightly sloping surface 34, 35 of the flange 2. It will be seen that the material of the flange 2 is sloping down laterally from the central portion 1 as indicated by the dotted lines 34-35. The same is the case in the upper part 30 of the frame as is indicated by the reference numerals 66-66. These sloping surfaces give strength to the main frame which may be a suitable casting or made in a drawing process. Bronze, aluminum or other material may be used for the frame. The circular recesses in the 35 sloping surface 34-35 provide proper seats for the shoulders (32, 33) on the pump cylinders. The cylinders project with their lower portions through the openings in the flange 2 of the main frame 1 as is indicated by the numerals 36, 37. 40 The lowest portion of each cylinder is further turned down as is indicated by the numerals 38, 39.

The frame 1 carries a laterally extending flange 40 integral with the frame and axially spaced 45 from the flange portion 2. This flange portion 40 is provided with an annular groove or recess for receiving a felt packing 41 or the like. Holes are provided in the flange 40 for the reception of auxiliary pistons such as the pistons 42, 43 shown 50 in the drawings. The auxiliary piston 42 cooperates with the main piston 44 contained within the pump cylinder 6, and the auxiliary piston 43 cooperates with the main piston 45 contained within the pump cylinder 9. There are as many 55 auxiliary pistons 42, 43, as there are main pistons 44-45, reciprocating within the pump cylinders such as 6 and 9.

The lower portion of each of the main pistons (44, 45) is formed into a head such as indicated 60 by the reference numerals 46 and 47, respectively. The head of each piston is provided with a set off shoulder as shown in the drawings, the diameter of which corresponds substantially to the 65 diameter of the lower portion of the cylinders designated in the drawings by the numerals 38,

39. The portions such as 36 and 37, respectively, of each cylinder, and the head with the shoulder on each piston serve for the reception of a spring such as is shown at 48 and 49. Thus, the spring 48 is disposed between the head 46 of the piston 44 and the shoulder 36 of the cylinder 6 and tends to pull the main piston 44 downwardly in the direction of the cooperating auxiliary piston 42; the spring 49 is disposed between the shoulder portion 37 of the pump cylinder 9 and the head 47 of the main piston 45, and gives the piston 45 a downward tendency in the direction of the cooperating auxiliary piston 43.

30 The same arrangement is duplicated with each of the other pump pistons and the corresponding cylinders. It is understood of course that there are as many pump cylinders and pistons as there are engine cylinders since each of the pump pistons and cylinders is intended to meter and measure the fuel for a specific one of the engine 35 cylinders.

39 Each of the auxiliary pistons (42-43) is disposed in a corresponding one of the circularly arranged holes in the flange portion 40 of the main frame. It is of a cylindrical form and provided 100 with a central boring for receiving a spring such as the springs 50 and 51. Each cooperating main piston has a counter drilled hole, and the spring extends with one end into this hole as shown, and into the central boring in the auxiliary piston. 105 The spring exerts thus a tendency on the corresponding auxiliary piston to separate the same from the main piston. For example, it will be seen that the main piston 45 or rather to say the head 47 of the piston 45 is separated from the auxiliary piston 43 in this particular position of the pistons. A sleeve is disposed on each of the auxiliary pistons. The sleeve cooperating with the auxiliary piston 42 is designated by the numeral 52, and the sleeve cooperating with the auxiliary piston 43 is designated by the numeral 53. Suitable lubricating grooves are provided on each of the cylindrical auxiliary pistons in order to provide for a good lubrication. The operation 110 of the auxiliary pistons relative to the main pistons will be described later on after several other structural details are explained.

40 A boring 54 is provided centrally within the lower portion of the main frame 1. This boring 54 serves as a journal or bearing for the bearing portion 55 of a rotary cam 58. This bearing portion 55 is provided with lubricating grooves such as 56 and 57, and with a transverse lubricating hole 58'. Integral with the bearing portion and extending laterally therefrom in disc form is the 115 cam plate 58 having the dwell 59. The lower splined portion 60 is also integral with the cam 58 and with the journal portion 55 thereof.

45 The splined portion 60 is disposed within an internally splined gear 28 journaled in the lower portion of the housing 27 by means of the bearing 61. This bearing is held within the bottom portion of the housing 27 by means of the nut 62 and by means of the closing member 63. The nut 62 engages the threaded end of the internally 120 splined bushing of the gear 28 while the member 63 is threaded into the internally threaded housing 27 as shown. The bearing 61 is thus held in engagement with the housing by the member 63, 125 while the driving member or gear 28 is held in position by means of the nut 62. The splined portion 60 of the rotary cam is disposed within the internally splined gear 28 and is therefore axially 130 movable therein and rotatable therewith. In 135

140 145 150

other words, the cam will rotate with the gear but can be shifted axially to the gear.

Laterally extending projections, such as 64, on the housing 27, register with the corresponding 5 projections (3) on the main frame. There are three such laterally extending projections which register with each other. The housing 27 is held in engagement with the main frame 1 by means of tubular screws such as the screw 65, one for 10 each pair of registering lateral extensions on the housing 27 and on the main frame 1, respectively. If it is desired to gain entrance into the interior of the lower portion of the device, it is therefore merely necessary to remove the tubular 15 screws (65) and to withdraw the housing 27 from engagement with the main frame. The rotary cam, the auxiliary pistons and the lower portion of the main pistons will thus be exposed for inspection.

20 The portion of the housing 27 within which the rotary cam operates will normally be filled with lubricating oil or grease. The device is intended to pump fuel oil or any other desirable fuel for the operation of an internal combustion. 25 This pumping of the fuel is accomplished by the pistons such as 44—45 reciprocating within the cylinders such as 6 and 9. The upper portion of the device which encloses the working end of the pump cylinders, and the lower portion in which 30 lubricating grease or oil is contained for lubricating the rotary cam, the splines 60, the bearings 61, and the journal 55, must therefore be separated. This separation is accomplished by the flange 40 on the main frame 1 and by the felt 35 packing 41 contained in the annular groove in the flange 40. It is therefore impossible for the fuel to seep through and to enter the lower portion of the housing 27 where the lubricating oil or grease is contained and it is likewise impossible for the 40 lubricating medium to enter the upper portion of the housing where the operating parts are located for the metering and pumping of the fuel. An opening such as 65' is provided in the flange 2 of the frame, and any fuel that may seep along 45 the pistons and cylinder walls down to the annular chamber 40' can be thrown out to the outside.

The mechanism contained in and cooperating with the upper portion of the device will be described next.

Near its upper end, the main frame 1 has a serrated flange 66. This serrated flange is represented by a number of semi-circular notches each provided for the reception of one of the pump 55 cylinders, such as the cylinders 6 and 9. The cylinders are thus nicely disposed on the main frame and held against radial displacement on one end by the serrated flange 66 and at the other end by the openings which receive the shoulder portions 60 (36 and 37) of the cylinders. A closing member 10 having an internal opening 67 is then put on these cylinders. The threaded upper portion 68 of the main frame extends through the opening 67 in the member 10. The bottom side of the 65 member 10 (as seen in Figure 3) is provided with a central boring and with circularly arranged borings, one for each cylinder. The cylinders fit each in a corresponding boring in the member 10 as shown in the drawings. Gaskets such as the 70 gaskets 68 and 69 are interposed between the head of the corresponding cylinder and the bottom of the corresponding boring in the member 10. It will be observed that each of these gaskets has a shoulder which engages the head surface of the corresponding cylinder. I have chosen this par-

ticular form of gasket in order to reduce the contacting surface and thereby increase the tightness of the joint. Centrally of each of the borings receiving the cylinder is a boring, in axial extension of the first boring, which extends through the entire member 10. These borings are indicated in the drawings Figure 3 by the numerals 70 and 71.

80 Next in assembly is a valve disk or valve plate indicated in the drawings by the reference numeral 72. This is a circular disk provided with a number of bosses (76—77) and through each of these bosses extends a hole, indicated by the reference numerals 74 and 75. An oil-tight fit between the valve plate 72 and the closing member 10 is obtained by means of gaskets, one cooperating with each of the bosses (76 and 77) and furnishing a tight joint between the valve plate 72 and the closing member 10. The gaskets cooperating with the bosses 76 and 77 are indicated by the reference numerals 78 and 79.

85 The bosses (76 and 77) extend slightly into the corresponding borings (70 and 71) in the member 10 and represent the valve seats for certain valves cooperating with the pistons (44 and 45) 90 as will be described presently.

95 On top of the valve plate 72 is a circular filter indicated by the reference numeral 80. This filter is provided with a central and a peripheral flange and these flanges cooperate with suitable 100 ring shaped gaskets indicated by the reference numerals 81 and 82.

105 The next member is the fuel inlet shell or top cap 23. This cap has a central boring for admitting the shaft of the bushing member 26, and a circular flange 83 which overlies the valve plate 72 and engages the turned down portion 84 on the closing member 10. The cap 23 has also an angularly projecting inlet member 85 provided with an external thread. Attached to this inlet member 85 may be the fuel line 24 by means of the nut 25.

110 When the fuel inlet shell or top cap 23 is assembled with the device as described above, a chamber 86 will be the result, which chamber is 115 divided into two parts by means of the filter 80. Liquid fuel entering the device through the fuel line 24 and through the boring 87 will therefore flood this chamber 86 on both sides of the filter 80. 120 Solid particles will collect in front of the filter and the filtered fuel will enter through the filter into the lower portion of the chamber 86 and will flood the borings such as 74 and 75 in the valve plate 72. This is the manner in which the liquid fuel is fed 125 to the device.

130 It should be remembered for proper understanding of the subsequent discussion of the operation of the device that the chamber 86 is flooded with liquid fuel and that the liquid fuel also floods the 135 borings such as 74 and 75 leading to the valves which cooperate with the corresponding cylinders and pistons. It is understood that the borings, such as 74 and 75, are axially in line with the corresponding pistons, such as 44 and 45.

140 Before entering upon a discussion of the operation of the device I will describe the remaining mechanism.

145 The upper part of the main frame 1 is formed into an axially extending projection 68. This projection is externally threaded for the reception of the closing bushing 26. The extension 68 is provided with an internal worm for the reception of the worm 88. The face of this worm is provided 150

with a screw driver slot 89, and with an internal key groove.

A central boring 90 extends through the frame for the reception of the control shaft 91. This shaft, at its lower end, is provided with a head flange 92. The shaft is inserted from the bottom of the device through the rotary cam and through the boring 90 in the frame 1 as well as through the worm 88. The shaft on its upper end is provided with a key groove 93 and this key groove is brought into register with the corresponding internal key groove in the worm 88. The shaft 91 is thus keyed to the worm 88 and the assembly is completed by means of a nut member 94 which has two projections 95 and 96 adapted to engage the screw driver slot 89 in the worm 88. The nut 94 is threaded on the corresponding threaded portion 97 of the shaft 91 until the projections 95 and 96 engage the surface of the worm 88. The shaft 91 is then dropped whereby the projections 95 and 96 are brought into engagement with the screw driver slot 89 in the worm 88, locking the shaft 91 to the worm 88. The upper end of the shaft 91 is squared as is indicated by the reference numeral 98.

Assembled with the top cap or inlet shell 26 are the following parts: A bushing having a flange 99 extends through the closing member 26 as shown. This bushing has a squared opening 100 for the reception of the squared end 98 of the shaft 91. The upper portion 101 of the bushing, which extends to the outside, is provided with a key 102 and with a threaded end 29. The control lever 30 is provided with a hole and with a key groove for attachment to the portion 101 of the bushing. The attachment is finally completed by attaching the nut 31 to the threaded end 29, thereby locking the control lever 30 in engagement with the member 26. An axial displacement of the lever 30 is thereby excluded, while a rotary movement of this lever is permitted. The squared opening 100 in the bushing which cooperates with the member 26 is brought into register with the squared end 98 of the shaft 91 and the member 26 is then tightened on the threaded end 68 of the main frame. This completes the assembly of the device as far as the same has been described.

The following operation will be apparent from the above description of the details and should be borne in mind for the subsequent discussion of the functions of the device.

The rotation of the control lever 30 will cause a corresponding rotation of the shaft 91 and, since the shaft 91 is keyed to the worm member 88, it will be apparent that a rotation of the lever 30 will cause a lifting or lowering of the shaft 91 within the device. The axial direction of the movement of the shaft 91 will depend on the direction of rotation of the control lever 30. The radial limit of rotation of the lever 30 will depend on the adjustable axial limit of movement of the worm member 88. The lever 30 will be limited in its movement to approximately 150 degrees.

When the lever 30 is rotated, the shaft 91 will move up or down, as the case may be, thereby moving the cam plate 58 up or down. This axial movement of the cam plate as a consequence of the lifting of the shaft 91 will be understood when it is considered that the shaft extends through the cam and that the head 92 of the shaft engages the splined portion of the cam. The force of the various springs cooperating with

the pistons engaging the cam will tend to keep the cam 58 down. When the lever 30 is rotated in the direction to shift the shaft downwardly the cam will follow. However, should the control lever 30 be turned to move the shaft 91 in the other direction, the head 92 will cause the lifting of the cam, and the splined portion of the cam will slide within the internally splined gear 28, upwardly, against the pressure of the springs cooperating with the pistons.

It is important that this operation of the control lever and of the shaft 91 relative to the cam plate 58 be kept in mind for an understanding of the subsequent explanations.

It may be mentioned at this point that the lower portion of the shaft 91 is relieved by a boring indicated in the drawings by dotted lines 105-106. This boring in the shaft extends approximately to the point designated by the numeral 107. Lubricating borings, such as 108 may be provided on the shaft 91 where the journal 55 of the cam engages the shaft in order to provide for good lubrication. The boring 105-106 extending to the point 107 in the shaft may be used for lubricating the cam and the other 100 internally disposed rotating operating parts.

I will now describe the structure and operation of the valves which cooperate with each of the pistons such as pistons 44 and 45. The upper portion of the piston 44 has been shown in cross-section in order to illustrate the arrangement of the various parts of the valve mechanism.

Each piston is turned down in its upper portion and provided with a central boring. This is particularly shown in connection with the piston 44, the turned down portion being indicated by the numeral 110 and the central boring in this turned down portion of the piston 44 being indicated by the numeral 111. The valve stem 112 is disposed within the boring 111. The valve 115 plug or head 113 which is integral with the stem 112 operates against the valve seat 76 closing the supply opening 74 which is in connection with the fuel supply chamber 86. The lower portion of the valve stem 112 is roughened as indicated in the drawings. A tubular sleeve member 114 is disposed around the turned down portion 110 of the piston 44 and is slidably thereon. The boring in the upper portion of the sleeve 114 is enlarged providing a shoulder 115. This shoulder registers with the lower edge of a transverse notch 116 in the turned down portion 110 of the piston 44. A key 117 is disposed in the transverse notch of the piston portion 110. The upper portion of the sleeve 114 is closed by a bushing 118 which is provided with a shoulder. A spring 119 is disposed between the valve head 113 and the shoulder on the bushing 118. This spring tends to keep the sleeve 114 on the turned down portion 110 of the piston 44 as shown in the drawings 125 and to pull the valve stem out of the boring in the piston.

The construction of this valve arrangement cooperating with each piston will be better understood with reference to Figure 5 which I will describe next.

Referring now to Figure 5, this figure shows, on an enlarged scale, the turned down upper portion of the piston 44. This portion is indicated by the reference numeral 110 in accordance with the like reference numeral applied to this part in Figure 3. It will be seen that this turned down portion 110 of the piston 44 is provided with a central boring 111 and disposed in this boring is the valve stem 112. The valve head is 150

not shown in these drawings Figure 5. The lower portion of the valve stem 112 is roughened as is indicated by the reference numeral 120. A transversal notch 116 is provided in this turned down portion 110 of the piston. A key 117 is placed within this notch and is adapted to establish engagement with the roughened portion 120 of the valve stem. The sleeve which surrounds the turned down portion 110 of the piston is shown in fragmentary section indicated by the numeral 114. The sleeve is slideable on the turned down portion 110 and the boring in the sleeve is enlarged in the upper portion as indicated by the numeral 121. A sloping shoulder 122 is thereby provided which is substantially in register with the lower edge of the transverse notch 116. Now, since the sleeve 114 is slideable on the turned down portion 110 of the piston, it will be apparent that the shoulder 122 will catch the key 117 and press the key against the roughened portion 120 of the valve stem 112 at the moment when the sleeve 114 moves on the turned down portion 110 of the piston in the direction shown in Figure 5 by the arrow. When the sleeve 114 moves thus, it will lock the valve stem 112 with the portion 110 of the piston. The unlocking can only be accomplished when the sleeve 114 moves or slides along the turned down portion 110 of the piston in the contrary direction.

30 The operation of the pistons and of the valve cooperating with each piston will now be described in detail with reference to the Figure 6.

This Figure 6 is a somewhat diagrammatic representation, on an enlarged scale, of the operation of the cooperating pistons and valves. A six cylinder pump device is assumed in this figure, that is to say, a pump device adapted to supply fuel in metered and measured quantities to a six cylinder internal combustion engine. The device may be of the structure shown in Figures 1 and 2, and the internal arrangement may be the one described with reference to Figure 3.

In order to simplify the explanation of piston and valve operation, I have shown the valve seats, and also the operating cam in straight line representation. Only a fraction of the cam, namely the cam dwell portion, is shown as indicated by the reference numeral 59 in accordance with the same reference numeral applied to this cam portion in Figure 3. It will be understood that the cam is in reality a circular rotating disc.

The valve seat plate which in reality is a circular plate such as indicated by numeral 72 in Figure 3 is also shown in a straight line plane, and the same reference numeral 72 is applied thereto. This valve plate 72 has as many valve seats as there are pump cylinders. The valve seats extend in reality into borings within a closure member such as the member 10 in Figure 3. The borings act in the nature of a chamber to which liquid fuel is admitted by the valves. It is assumed in Figure 6 that the first valve seat corresponds to the valve seat 76 shown in Figure 3 in axial alignment with the piston 44, the upper portion of which is represented in cross-section. The next two valve seats are designated by numerals 125 and 126.

The valve seat 77 corresponds to the valve seat 76 in the circular structure Figure 3. The remaining valve seats disposed in the (circular) structure between the valve seats 76 and 77 are designated by numerals 127 and 128.

The cylinders are omitted, and only the upper portions of the pistons in axial alignment with the valve seats are shown. Accordingly, the first

piston shown in the drawings Figure 6 on the left side, is the (upper part) piston 44 corresponding to piston 44 of Figure 3. The piston 45 is shown in alignment with valve seat 77 and corresponds to the piston 45 in Figure 3. The (upper portion of) other pistons are designated by reference numerals 129 to 132, inclusive.

In the lower portion of the drawings Figure 6 is shown the cam 59, and it is assumed that this cam moves (in rotating) in the direction of the arrow, i. e., from right to left in Figure 6. It may be mentioned here that the direction of movement of the cam is immaterial in practice, but a definite direction of movement is assumed for the purpose of convenient description. Auxiliary pistons ride on the cam. These pistons can reciprocate or shift axially within the corresponding holes in the lower flange of the main frame of the device and within the sleeve on the piston, as particularly shown in Figure 3.

Part of the auxiliary piston 42 is shown in Figure 6 and designated by the same reference numeral. Part of the auxiliary piston 43 is shown likewise. The remaining auxiliary pistons cooperating with the pistons 129 to 132, are marked by numerals 133 to 136, inclusive.

The operation will be described with particular reference to Figure 6, but Figure 3 should be consulted for certain details not shown in Figure 6. The previously mentioned operation of the auxiliary pistons relative to the main piston should be recalled, namely, that these auxiliary pistons have a constant stroke depending on the dwell 59 of the rotary cam 58. The downward stroke of the main pistons is fixed due to the sleeves such as the sleeves 52 and 53 shown in Figure 3. The flanged heads on the pistons will engage the sleeves as is apparent from the position of piston 45 relative to the sleeve 53. The flanged head 47 of the piston 45 rests on the sleeve 53. In case the cam is shifted axially by the actuation of the control lever 30, the auxiliary pistons will be lowered or raised relative to the main pistons.

For example, if the cam 58 is lowered from the position shown in Figure 3, the result would be that all auxiliary pistons would move downwardly, following the movement of the cam. The pistons which engage the plane of the cam, such as the piston 43 would move down and the distance 137 (Figure 3) between the auxiliary piston and the head of the main piston 45 would increase. The main piston remains in the position shown because the head 47 rests on the sleeve 53. The auxiliary piston which is in engagement with the highest point of the cam dwell 59 would also follow the downward motion of the cam. However, since this piston is in its highest position and has lifted the main piston 44, the main piston would also follow the movement and the distance 138 (Figure 3) would decrease. This distance 138 signifies the stroke of the piston 44 (and also the remaining pistons) at the particular cam setting. A lowering of the cam from this setting therefore means a decrease in the stroke of the main pistons, and raising of the cam will cause a corresponding increase.

In case the cam is lowered to such extent that the distance 138 is completely obliterated, that is to say, that the main piston will rest on the sleeves such as 52, 53 in the highest position of the auxiliary piston, there will be no pumping of fuel; the main pistons will not respond. The auxiliary pistons will still have their constant stroke depending on the cam dwell 59, but will reciprocate idly within the space 137 which is now increased to the amount of the cam dwell 59.

In the position shown in Figure 3, and, in fact, in any effective working position, the auxiliary pistons will always operate with constant stroke, but only part of the stroke will be operatively transmitted to the main pistons.

When the main piston moves down, the valve on its upper end, connecting with the fuel supply, must open to admit the liquid fuel to the space within which the upper portion of the piston reciprocates. In the moment when the piston moves up, i. e., when it starts its working stroke, the valve must close, so that the piston can displace the liquid fuel in the corresponding space and eject the fuel through the outlet connection. This opening and closing of the valve cooperating with each of the cylinders and pistons is accomplished by means of the novel valve lock which I have previously described particularly with reference to Figures 3 and 5.

With the above explanations in mind, I will enter upon a description of the function of the device with particular reference to Figure 6, but, as I have said previously, Figure 3 should be consulted for details not shown in Figure 6.

Now, let us assume that the cam rotates there-by moving the dwell 59 in the direction indicated by the arrow in Figure 6. The auxiliary piston 42 is now positioned on the plane of the cam. The valve head 113 is in engagement with the valve seat 76 closing the opening 74. The chamber 70 (Figure 3) is flooded with liquid fuel. The cam rotates and the cam dwell will lift the auxiliary piston to a position as shown in connection with the second piston 133. Let us assume that the working stroke begins at this point. The piston 44 (129) will move upwardly and will displace the liquid fuel in the corresponding chamber, ejecting the fuel through the outlet channel such as 139, as shown in Figure 3. In the further movement of the cam, the auxiliary piston will finally take the position shown in connection with the piston 134. The highest point of the cam dwell 59 is somewhat flattened as is indicated by the dotted line 140. The piston will therefore come to a stop in its upward motion. It will remain in this position for the length of the flattened portion 140 of the cam dwell. Since the sleeve 114 is slideable on the turned down portion 110 of the piston, and since the inertia of the sleeve overbalances the force of the spring 119, the sleeve 14 will have a tendency to continue in the motion of the piston and will compress the spring 119 as is shown in connection with the piston in the highest portion of the cam.

The shoulder 122 will engage the key 117 and will press the key against the roughened lower portion 120 of the valve stem. The sleeve 114 remains in this position due to the inertia of the material, which action will be understood when it is considered that the inertia of the sleeve 114 overbalances the spring 119. The valve stem 112 is therefore locked in engagement with the turned down portion 110 of the piston (130). The working stroke is completed and the quantity of fuel which was previously admitted into the chamber 70 (Figure 3) is ejected through the outlet duct 139.

The cam continues to rotate and the cam dwell moves away from under the piston so that the piston comes into the position shown in connection with the auxiliary piston 43. The cooperating piston moves downwardly. It takes the valve along due to the locking of the valve stem 112 in engagement with the turned down portion 110 of the piston. The inlet opening (such as

75) is released by the action of the valve head 113 and the liquid fuel enters the chamber such as 70 in Figure 3. The piston moves further down due to the operation of the cam and finally assumes the position shown in connection with the auxiliary piston 135. The valve is completely open and liquid fuel is admitted into the cylinder pumping chamber.

The axial movement of the main piston will come to a sudden stop, during the return movement at the moment when the flange of the main piston engages the sleeve of the corresponding auxiliary piston. The sleeve 114 due to the momentum of the material will tend to continue in the downward motion and will assume the position shown in the drawings in Figure 6, (piston 131) releasing the key 117 and thereby releasing the valve stem 112 from locking engagement with the piston. The force of the spring 119 will now become effective and will move the valve upwardly to close the corresponding valve seat opening as is shown on the right side of the drawing Figure 6.

The valve in the piston is now again in the position in which it originally was. Liquid fuel has been admitted to the cylinder chamber; the auxiliary piston rides on the plane of the cam, and when it is raised to the position shown in connection with the auxiliary piston 133, the working stroke will begin and the liquid fuel will be ejected through the outlet duct as described. When the piston arrives again at the highest point of the cam dwell 59, which is flattened, the sleeve will again continue in the working stroke movement, will compress the spring and will lock the valve in engagement with the piston. On the return motion, when the piston is at the end of the down stroke, the sleeve 114 will move again and will release the lock of the valve. The valve will close and the pumping operation of the piston will be accomplished during the next working stroke. The cycle is repeated as long as the device is in operation.

It will be seen from the above description of the valve action that this cooperating piston and valve structure accomplishes the desired purpose in novel manner. The sleeve on the turned down portion of the piston acts in the nature of a chuck for locking the valve to the piston at the end of the working stroke, and for releasing the locking engagement at the end of the return stroke. The valve is positively opened and liquid fuel is admitted during the return stroke, and at the end of the return stroke, the valve is released and closes the inlet port due to the spring force. The spring need only be strong enough to lift the weight of the small valve stem and valve head. The weight of the sleeve is many times the force of the spring. I therefore utilize the inertia of the material for accomplishing the valve action, and this utilization of natural forces enables me to achieve a proper and positive action in this device, in a novel manner, and with less effort than was thought possible in the past.

Attention is called at this point of the description to the length of the pump pistons. A seeping of fuel along these long pistons will be practically negligible even in case of highest pressures. It will also be realized that the construction of the pump relative to the volume handled can be readily modified without any effort. The borings in the pump cylinders can be enlarged, or rather to say, other cylinders with larger borings can be substituted together with other pistons, and inserted in place of the pistons shown.

This will increase the capacity of the pistons for a proportionately larger engine.

I also want to call attention to the relatively long cam dwell. The ejection of the fuel into the cylinders of the engine is thereby accomplished gradually, during the compression stroke of the engine pistons.

The structure of the valve cooperating with each pump piston may, of course, be modified in various ways. The essential thought resides in the utilization of the natural forces, that is, in the inertia that is in the material. In the Figures 7 to 10 inclusive are shown two further embodiments of cooperating valves and pistons which I will describe next.

In Figures 7 and 8 I have shown the upper part of a piston, designated by the reference numeral 140. The upper portion consists of two cooperating sides 141 and 142, whereby the part 142 is loosely attached to the part 141. The arrows at the left of Figures 7 and 8 indicate the downward and upward motion of the piston, respectively. The cooperating parts 141 and 142, the first being integral with the piston 140, are provided with a cavity in which are disposed rings as indicated by the reference numerals 143 to 147, inclusive. The valve comprises a stem 148 and a head 149. The latter may cooperate with a valve seat to close or to open a port leading to the cylinder chamber.

Let us now assume that the piston 140 moves upwardly as is shown in Figure 8. The valve at this moment is closed. At the end of the working stroke, the part 142 will continue to move due to the inertia of the material, and will assume the position relative to the part 141 of the piston 140 in which it is shown in the drawings Figure 7. The rings 143 to 147, inclusive, will be tilted within the cavity of the parts 141 and 142 and will thereby grip the roughened valve stem 148. The piston 140 moves then downwardly in the direction shown by the arrow on the left of Figure 7 and, since the valve stem 148 is locked in engagement with the piston, the piston 140 will take the valve 149 along, thereby opening the supply orifice. At the end of the return stroke, the part 142 will again return to the position shown in Figure 8, thereby releasing the valve 149. The closure of the valve may be accomplished by the use of a spring as in the previous case.

In Figures 9 and 10 is shown a further modification which may be employed. The end of the piston such as the piston 150 is turned down at 151 and provided with a chuck head 152. A boring is provided in the turned down portion 151 as shown, and a longitudinal slot gives resiliency to the upper portion of the piston. A chuck sleeve 153 is slidably disposed on the turned down portion 151, and the upper part of the chuck portion 153 is turned in conically at 154 for engagement with the conical back of the head 152. The valve stem 155 is disposed within the slotted opening of the piston 150.

Assuming now that the piston 150 moves upwardly in the direction of the arrow shown on the left of Figure 10, with the valve closed, the piston will displace the liquid fuel and eject the same through the outlet duct of the corresponding cylinder. At the end of the working stroke, the inertia of the slidable chuck sleeve 153 will cause this part to slide upwardly to the position shown in Figure 9. The conical surface 154 engages the corresponding surface of the head 152 of the piston, thereby locking the resilient sides of the slotted head and gripping the stem 155. The

valve is now locked to the piston. During the downward motion in the direction of the arrow shown on the left in Figure 9, the valve will be taken along by the piston due to the locking of the chuck sleeve 153, and the valve will open and liquid fuel will be admitted into the corresponding cylinder chamber. At the end of the down stroke, the chuck sleeve will move due to the momentum of the return motion of the piston and will assume the position as shown in Figure 10, releasing the valve stem 155. The valve can now move to close the supply orifice in a manner as was previously described.

It will be understood that the embodiments shown in Figures 7 to 10, inclusive, are merely diagrammatic representations of additional structures which may be used in practice. These examples do not by any means exhaust the ideas of modifications and other embodiments which may occur to one experienced in the art and directed by my teachings.

The valve head or valve plug which I have shown as a plate or flat disc may of course be rounded, or may be made in conical plug form, if desired.

I will next describe the check valve which is disposed in each of the outlet connections of the device.

Threaded outlet extensions are provided on the closure member 10 in radial alignment with the corresponding cylinders. Two such outlet extensions are shown in Figure 3 and designated by the numerals 156 and 157. Each extension is provided with an external thread and with an outlet duct such as the duct 139 shown in connection with the extension 156. The extension 156 is in radial alignment with the cylinder 6 and the extension 157 is in radial alignment with the cylinder 9. There are as many such outlet extensions as there are cylinders. Each outlet extension is provided with a socket boring and disposed at the bottom of this socket boring is a gasket such as is indicated by the reference numeral 160 in connection with the extension 156. A valve seat member 161 is disposed in the socket opening engaging the gasket 160. This member has an internal boring 162 and a threaded head 163 which is flattened on its sides in order to permit the passage of fuel. A gasket 164 is provided on the flange of the member 161 and engages a flange 166 of the member 17 which is held in assembly with the valve seat member 161 and with the extension 165 by means of a nut such as the nut 11. This member 17 is provided with a boring 168 and a larger boring 169. A valve housing 170 is disposed within this large boring 169 as shown. The valve housing is provided with an internal thread for engagement with the external thread on the valve seat head 163 and the bottom of this valve housing 170 is slotted as indicated by the reference numeral 172. The face of the head 163 represents the valve seat for the valve 173, the stem 174 of which is disposed within the bottom boring of the valve housing 170. A spring 175 tends to close the valve 173 in engagement with the valve seat on the face of the head 163.

The above structure is shown in enlarged cross-section in Figure 4 which is taken along the lines 4-4 in Figure 3. It will be seen that the valve 145 housing is slotted at its end as indicated by the numeral 172, and that this slotted end of the valve housing engages the threaded portion 163 of the valve seat which is provided with the flattened sides. The fuel entering the valve, housing 150

can therefore be displaced through the slotted end and can flow along these flattened sides of the valve seat.

When the cylinder 44 operates on its working stroke to eject the liquid fuel through the duct 139, the fuel will enter through the hole in the gasket 160 and through the duct 162 in the valve seat member 161. The pressure of the fuel due to the operation of the piston 44 will displace the valve 173 against the pressure of the spring 175 and the fuel will enter into the valve housing 170. It will leave through the slotted end of the valve housing which is in engagement with the valve seat head 163, the sides of the head 163 of the valve seat being flattened in order to permit an easy passage of the fuel. The fuel will thus flow around the valve housing 170 and will enter the outlet duct 168 in the member 17. Attached to the member 17 by means of a suitable screw joint or the like is a corresponding fuel line leading to the atomizer in the corresponding engine cylinder.

A check valve arrangement of the structure described above is disposed in all the fuel outlets on the member 10 in radial alignment with the corresponding cylinders.

The operation will be easily understood from the above detailed description of the mechanism. However, for the sake of completeness, I will briefly review the operation below so that the device may be correctly understood. The fuel is fed to the device by the fuel inlet line 24 and thus to the supply chamber 68 on both sides of the filter 80. In the continuous operation of this device it must be assumed that the various channels and ports are flooded with liquid fuel. Therefore, it is merely necessary to displace the fuel rather than to pump it into the device by the action of the pistons.

Since the supply chamber 86 and the supply ports such as 74 and 75 of the various cylinders are flooded with liquid fuel, the operation of the pistons merely causes a displacement of the fuel. When the cam 58 rotates due to the rotation of the driving member 28, it will actuate the auxiliary pistons, and, according to the adjustment of the control lever 30, the auxiliary pistons will actuate the main pistons such as 44 and 45. The main pistons will cause the opening of the valves of the supply ports in a manner as was particularly described in connection with the Figure 6 and the fuel will enter the chambers such as 70, while the pistons go down. The valves will then close and during the working stroke of the pistons, the fuel within the chambers such as 70 will be displaced and will be ejected through the corresponding ducts such as 139. The pressure on the fuel will cause an opening of the check valves such as 173 in the corresponding outlet opening and the fuel will flow from the duct 162 into the valve housing and around the slotted end of the valve housing joining the flattened sides of the corresponding valve seat, and partially also through the bearing in which the valve stem (174) reciprocates, entering finally the outlet duct (168) which is in connection with the pipe line leading to the atomizer on the corresponding engine cylinder.

When it is desired to supply less fuel for the operation of the engine, all that is necessary is to turn the control lever 30 in a direction to shift the shaft 91 downwardly, whereby the cam 58 will follow the movement of the shaft due to the pressure of the auxiliary pistons on the cam. The stroke of the main pistons will thus

be reduced as desired and the pistons will supply less fuel through the pipe lines to the engine cylinders. When it is desired to supply more fuel, in accordance with the requirements of speed and load, the control lever will be rotated in the contrary direction, lifting the shaft 91, thereby also lifting the cam 58 due to the fact that the head 92 of the shaft engages the face of the splined portion 60 of the cam, and the cam will be raised, increasing thereby the effective stroke of the main pistons.

It will be seen that the auxiliary pistons are directly in sliding engagement with the cam. If desired, this arrangement may be modified, for example, in accordance with the structure shown in Figure 11.

Referring now to Figure 11, this figure shows a fragmentary portion of a cam such as the cam 58, designated in Figure 11 by the reference numeral 58'. The lower end of a pump cylinder is shown in this figure and designated by the numeral 180. A piston 181 reciprocates within this cylinder 180. The lower end of this piston has a cup-like head 182 having an opening for receiving the auxiliary piston 183. The head 182 of the main piston at the end of the return stroke rests on the flange 40' of the main frame, corresponding to the flange 40 in Figure 3. The flange is also provided with an annular groove for receiving a felt packing 41' in order to prevent the communication of liquid fuel which may seep along the pistons with the lubricant contained in the lower portion of the housing, a portion of which is shown at 27'. A spring 184 engages the head 182 of the main piston 181, and at the other end, this spring 184 may engage a flange or shoulder on the cylinder 180. The spring therefore tends to keep the piston 181 in the lowermost position with the cup-like head 182 in engagement with the flange 40' of the main frame of the device.

The auxiliary piston 183 is provided with a wheel 185 which rolls along the periphery of the cam 58'. A spring 186 tends to move the auxiliary piston downwardly away from the main piston 181. A lowering of the cam 58' will therefore cause a corresponding lowering of the auxiliary pistons, while the main pistons remain in the position as shown in connection with piston 181.

The operation is therefore exactly the same as in the previously described embodiment. The modification resides chiefly in the provision of a roller or wheel 185 at the end of each auxiliary piston. In the previously described embodiment, the auxiliary pistons slide directly on the cam, while in this modification each auxiliary piston is provided with a roller.

A slot 187 is provided in the flange 40' in the main frame adjacent the opening in which the corresponding auxiliary piston reciprocates, and each auxiliary piston has a lateral projection such as the projection 188 which slides in this slot. The purpose of the slot and the corresponding projection of the piston is to fix the piston radially while permitting its longitudinal movement. This is necessary in view of the fact that a roller is provided at the end of the piston which cooperates with the cam. The auxiliary piston must therefore be prevented from rotating.

It will be understood that numerous modifications may be devised above and beyond the modifications of certain parts which I have shown and described. I therefore want to have it under-

stood that I do not desire to be limited in the application of the invention to the precise structure or structures shown and described in this specification, but only to the meaning and scope 5 of the claims which follows. I have expressed in these claims what I believe is new and distinguishing in the art.

What I claim as my invention is:

1. In a high speed fuel pump for internal combustion engines, a cylinder, a piston therefor, an axial boring in said piston, a valve having a stem disposed within said axial boring, a key member in the wall of said piston, and a sleeve on said piston for actuating said key member to lock 10 said valve stem to said piston upon the termination of the working stroke thereof.

2. In a fuel pump for internal combustion engines, a cylinder, a piston therefor, an axial boring in said piston, a valve member having a stem and a plug, said stem being disposed within 20 said axial boring, an inlet port for said cylinder, said plug being adapted to close said inlet port, key means for locking said valve member in engagement with said piston and sleeve means on said piston for actuating said key means upon the termination of the working stroke thereof and for releasing said valve member from locking 25 engagement with said piston upon the termination of the return stroke thereof whereby said valve member will open said inlet port during the return stroke and close said inlet port during the working stroke of said piston.

3. The unitary assembly of a fuel supply device for an internal combustion engine, comprising a frame, a plurality of cylinders circularly disposed 35 on said frame, a piston within each cylinder, a single rotary cam for actuating said pistons, means for altering the position of said cam axially relative to said pistons to determine the working stroke of said pistons, a member for securing 40 said cylinders in circular assembly on said frame, fuel inlet chambers in said member one for each cylinder and in axial alignment therewith, fuel outlet means extending laterally from said member, a valve plate cooperating with said member, valve seats on said plate extending individually 45 into said inlet chambers, a top shell for said device, a circular filter within said shell, a fuel inlet on said shell, and a single means cooperating with said frame for securing said shell, said valve plate, said member and said cylinders in position.

4. In a pump, an inlet port, a piston, a valve for said inlet port, said valve having a stem disposed slidably in said piston, a sleeve on said piston, a spring disposed between said sleeve and 50 said valve and tending to pull said stem from said piston, and means actuated by said sleeve for locking said stem to said piston upon the

end of the working stroke thereof, the piston pulling said valve locked thereto during the back stroke to open said port, and for unlocking said stem upon the termination of said back stroke, said spring pulling said valve to close said port. 50

5. A fuel pump for internal combustion engines comprising a casing, a plurality of cylinders disposed symmetrically around said casing, pistons for said cylinders, a shaft extending centrally through said casing, a cam for actuating said pistons, said cam being rotatably carried on said shaft, means secured to said casing and directly engaging said cam for rotating the same to actuate said pistons successively, and rotatable lever means disposed centrally of and outside said casing for shifting said shaft longitudinally to alter the position of said cam relative to said pistons for determining the stroke of said pistons. 55

6. A fuel pump mechanism of the class described, comprising a frame, a plurality of cylinders mounted symmetrically on one end of said frame, pistons for said cylinders projecting from said frame at one end, a rotatable cam for actuating said pistons, said cam being journaled within said frame, a housing for attachment to said frame to envelop said cam, a partition on said frame disposed within said housing for separating said cam from said cylinders to avoid seepage of fuel into said housing, means mounted in said housing and directly engaging said cam for rotating the same, a shaft extending centrally through said cam, a head on said shaft engaging said cam at one end thereof, a worm member disposed within said frame and cooperating with the other end of said shaft, and rotatable lever means mounted 100 outside said mechanism and centrally thereof for actuating said worm to move said shaft longitudinally for altering the position of said cam relative to said pistons to determine the stroke thereof. 105

7. A unitary fuel pump device comprising a cylinder, a piston therein, means for biasing said piston in the direction of the return stroke thereof, a stop for defining the extent of the return stroke, a hollow auxiliary piston disposed in axial 110 alignment with said first piston and adapted to actuate said first piston, spring means in said auxiliary piston tending to move the same away from said first piston, a rotatable cam for directly actuating said auxiliary piston, means 115 directly engaging said cam for rotating the same, a shaft extending centrally through said cam, a flange on said shaft engaging one end of said cam and rotatable lever means on said device for longitudinally moving said shaft to alter the 120 position of said cam relative to said piston for determining the stroke thereof. 125

FRITZ STEPHAN.
